UNITED STATES PATENT OFFICE.

KALLE W. WIRTANEN, OF NEW YORK, N. Y.

WRENCH.

Application filed May 18, 1921. Serial No. 470,642.

To all whom it may concern:

Be it known that I, KALLE W. WIRTANEN, a citizen of the United States, and resident of 210 West 147th St., New York, in the 5 county of New York and State of New York, have invented certain new and useful Improvements in Wrenches, of which the following is a specification.

This invention relates to wrenches in general and particularly to a kind adapted for universal use, provided with automatically operating jaws insuring an instantaneous grip upon the article to be engaged thereby.

One of the prime objects of my invention 15 is to provide a simple, effective device which will permit a manual rough adjustment of the distance between the jaws, and an automatic fine adjustment therebetween when gripping an article.

20 A further object of my invention is to provide means whereby such instantaneous gripping operation is assured without any lost motion of the wrench proper.

A further object of my invention is to 25 sign this instantaneous gripping means in such a way as to progressively increase the grip upon the article engaged by the wrench when the latter is moved in one direction, and to instantaneously release that article 30 when the wrench moves in opposite direction without any lost motion of the wrench proper.

Another object of my invention is to provide means whereby the jaws when automatically 35 fine adjusting themselves move toward each other at a constant angular relation with each other.

A further object of my invention is to 40 provide in connection with this progressively grip increasing means, exchangeable jaws adapted to be set at either an angle or in parallel relation to each other, thus facilitating the wrench being used as either a pipe or monkey wrench, respectively.

45 The foregoing and still further objects will be more fully apparent from the following description and the accompanying drawings showing preferred forms of my device, and forming part of this specification, and 50 in which:

Fig. 1 is a side elevation of my device.
Fig. 2 is a front elevation thereof.

Fig. 3 is a side elevation of my device, partially in section.

Fig. 4 is a side elevation of my device in 55 operation when gripping a pipe.

Fig. 5 is a cross sectional view taken on line 5—5 of Fig. 3.

Fig. 6 is a bottom detail view of a preferred form of the carriage. 60

Fig. 7 is a side elevation of my device with exchangeable, parallelly disposed jaws gripping a nut.

Fig. 8 is a cross sectional view of my device taken on line 8—8 of Fig. 7. 65

Fig. 9 is a perspective view of a preferred form of an exchangeable jaw.

Fig. 10 is a side elevation of a modified form of my device with differently designed exchangeable jaws. 70

Fig. 11 is a front elevation thereof.

Fig. 12 is a top view in full lines of an exchangeable jaw in the position shown in Fig. 10.

Fig. 13 is a side elevation of the exchangeable jaw shown in Fig. 10, in the position indicated in broken lines. 75

Fig. 14 is a side elevation of a modified form of wrench shank with an exchangeable jaw. 80

Fig. 15 is a detail view of the exchangeable jaw registering with the modified shank.

Fig. 16 is a cross sectional view taken on line 16—16 of Fig. 15.

Fig. 17 is a front elevation of the head of 85 the modified shank.

Fig. 18 is another preferred form of my wrench with automatically self-adjusting upper and lower jaws.

Fig. 19 is a perspective view of a preferred 90 form of a slide.

Referring to the drawings, and particularly to Figs. 1, 2, 3, 4, and 5, a unitary shank 1 is illustrated provided with a gear rack 2 on its inner face, and an enlarged 95 head 3, having a roughly toothed jaw portion indicated at 4.

The upper or gear rack portion of the shank is so constructed that the inner and outer faces are parallel to each other, while 100 the lower portion below the rack is tapered, as indicated at 5 or may be equipped with a wooden handle or otherwise shaped for convenient use.

Slidably mounted upon the rack portion of the shank is a carriage 6, having a longitudinal slot 7 registering with the shank, which provides a perfect guide for the carriage. The body of the carriage is provided with a window indicated at 8, in which operates a conventional worm 9, rotatably mounted upon a pin 10 and which engages the gear rack 2.

- 10 The upper surface of the carriage is beveled as indicated at 11 and protruding beyond that beveled surface upward, is an extension 12, the upper surface 13 of which is beveled at the same angle as is surface 11. 75
 15 At about its center, the extension 12 is provided with a longitudinal guide slot 14, the function of which will be explained later. 70

The carriage may be either made of one solid piece as shown in Fig. 3, or may be 20 made of two pieces as shown in Figs. 1, 2, and 6. The latter construction comprises a U-shaped member 6' embracing the outer and the side faces of the shank, while the solid member 6'' faces the rack. Thus a 25 longitudinal slot 7' is formed for receiving the shank.

Adapted to glide upon the beveled face 11 is a yoke-shaped slide member 15, embracing the outer side faces of the shank 30 above the carriage. In normal position, the bridge 16 of the yoke 15 abuts with the outer shank surfaces and is flush with the outer bridge part 17 of carriage 6.

Attached between the side portions of yoke 35 15, is a removable jaw 18, provided with a serrated gripping surface 19, which is disposed at a certain angular relation to jaw 4 of the shank, as is clearly shown by extension lines I and II in Fig. 1. Extension 40 line III indicated the plane of beveled portion 11 of both the carriage and the slide.

Secured to exchangeable jaw 18 in any 45 convenient manner is a spring member 20 for causing the jaw 18 to be normally disposed at a small distance from the inner surface 21 of shank 1, while at the same time causing bridge 16 of yoke 15 to abut with the outer surfaces of the shank.

The lower surface 22 of exchangeable jaw 50 18 may be so arranged as to glide upon the upper beveled surface 13 of extension 12 or to rest upon a connecting bridge of the slide as will be explained. In order to positively guide the slide and prevent it from disengaging the carriage 6, a pin 14' with two parallel surfaces is passed through the sides of the slide and guide slot 14, contacting with latter's parallel surfaces.

Referring now to Figs. 7, 8, 9, 14, 15, 16 60 and 17, the jaw portions of my wrench may be made exchangeable so that for the lower jaw 18, having the serrated gripping surface 19 disposed at an angle in relation to gripping jaw 4, another jaw member 23 may 65 be exchanged possessing a knurled gripping

surface 24 which is parallel with the knurled gripping surface 25 of an exchangeable jaw 26, shown in perspective view in Fig. 9.

Both of the jaws may be provided with dovetail extensions, for instance, jaw 23 70 with a dovetail extension 27, while slide 15 is correspondingly shaped as indicated at 28. By means of through-going screws 29, jaw 23 is positively secured to slide 15.

The exchangeable upper or shank jaw 75 26 is provided with a dovetail slot 30, while the head of the shank is accordingly shaped. By means of screw 31, the upper jaw is securely held to the head.

When using jaws parallelly disposed to 80 each other my wrench takes the place of a monkey wrench; while when the beveled jaw is inserted, my device becomes a pipe wrench.

In Figs. 14, 15, 16, and 17, a modified form 85 of shank head 3 is shown, shaped in such a manner that its side faces are in line with the shank proper, in contrast with the shank head shown in the formerly mentioned figures, where the head is broader than the 90 shank itself.

The exchangeable gripping jaw 32 fits with its parallel face 33 into a recess 34 provided in head 3'.

At both sides of the jaw proper there are 95 provided half-round wings 35, equipped with an aperture for receiving the screw 36. Wings 35 are adapted to straddle head 3 and screw 36 is then passed through both wings and the head, as indicated in Fig. 17. 100

Referring to Figs. 10, 11, 12, 13, and 19, a modified form of my device is shown where slide 115 is made of one closed piece, its sides being connected by a bridge 37, which is adapted to slide with its lower beveled surface 112 upon the upper beveled surface 113 of extension 122 of carriage 106.

At approximately the center at 38 of bridge 37, there may be attached to the slide, resilient means 120 for causing slide 110 115 normally assuming the position shown in Fig. 10. Upon the upper surface 39 of bridge 37 comes to rest the lower surface of exchangeable jaw member 40, shown in detail in Figs. 12 and 13, and which is so constructed that two of its sides 41 and 42 are of equal length while one gripping face 43 adjacent to side 41 is knurled and forms with side 41, a right angle as indicated at 44. The other gripping face 45 forms an 120 angle of less than 90° with the adjacent side 42 as shown at 46.

The front portion of the jaw member indicated at 47 extends beyond the jaw member proper and faces 48 and 49 are made 125 parallel to faces 41 and 42 respectively, and are adapted to rest upon the upper beveled surfaces 50 of the sides of the slide.

Head 103 of the shank is provided with a permanent knurled gripping jaw 51 and 130

has a dovetail undercut 52 for receiving the dovetail portions of another jaw member 53, provided with a serrated gripping face 54.

It will be noted that there is provided a space within the jaw member 53 indicated at 53 and side spaces 56 allowing for the spreading of gripping face 51.

By means of screw 57 passing through the sides of jaw member 53 and through the head 103, the jaw member 53 may be fixedly secured to the head.

When it is desired to use my device as a pipe wrench, jaw member 40 is placed in the position shown in Fig. 10 so that the serrated gripping surface 45 is disposed opposite the serrated surface of exchangeable jaw 53. When thus set the jaw 40 is attached by means of screws 129 to the sides of slide 115, which screws pass through apertures 58 and 59.

When it is desired to use my device as a monkey wrench, screws 129 then pass through apertures 58 and 60. In this manner the knurled surface 43 becomes the gripping surface. Simultaneously the upper jaw 53 is removed, whereby the knurled gripping surface 51 comes in action. Both of the knurled surfaces are then parallel and my device is then adapted for use as a monkey wrench.

In Fig. 18 I have shown one of the possible designs involving automatically fine adjusting jaws which indicates that I not only intend to use one stationary and one automatically fine adjusting jaw, but that I intend to apply such automatically adjusting jaws to both gripping ends of the wrench.

When my device is used as a pipe wrench as shown in Fig. 4, carriage 6 is roughly adjusted to the size of the pipe or any other article indicated at 61, then the jaws are brought down upon the article, whereby slide 15 is caused to move in the direction indicated by arrow IV. Slide 15 being forced to glide upon the beveled surface 11 moves in transverse direction to the direction of operation of the wrench, but also shifts toward stationary jaw surface of head 3. In this manner the article 61 is instantaneously gripped between the jaws, and the grip is progressively increased during the downward motion of the handle of the wrench.

Through the construction of my device, it is evident that the angle at which the jaws are set remains always constant, while the distance between the jaws is changed due to the automatic fine adjustment, when an article is being engaged by the jaws.

The moment the pressure is released, that is when the handle of the wrench is swung in opposite direction, spring 20 causes slide

15 to move to its normal position, and the grip of the jaws upon the article is instantly released.

When pipe 61 is to be turned the shank 1 is brought back again and the same automatic gripping procedure takes place, as described above.

It will be found that there is absolutely no lost motion in the movements of the wrench proper, as the article is gripped instantaneously in such a secure manner that any slip is positively eliminated.

The above feature is of particular importance when my device is used as a monkey wrench and especially when used upon nuts. In order to convert the pipe wrench into a monkey wrench, the gripping jaws are set parallel with each other. The carriage is then roughly adjusted by means of worm 9 engaging rack 2 so that the jaw faces are sufficiently apart to grip the sides of the nut.

When pressure is applied upon shank 1, the pressure is transmitted by means of the beveled surface 11 to slide 15, and thus the jaw 23 which moves in opposite direction to the movement of the shank or rather remains stationary while the wrench proper is moved, is pressed toward the other jaw.

Due to this operation the grip upon the nut is greatly increased and made absolutely positive, thus preventing any slips, which is generally the case in wrenches used heretofore.

One of the most important features of my invention is that when re-gripping an article, it is not necessary to manually re-adjust the distance between the jaws, since they automatically re-adjust themselves by means of the slide gliding upon the beveled surface of the carriage, which means a great saving of time and labor besides being of unexcelled convenience to the user.

This feature applies to my device when used as either a pipe wrench or monkey wrench, both of which latter types now in use necessitate frequent manual re-adjustment while in operation.

By following exactly the operation of my device when clamping an article, it will be noted that the jaws once brought into engagement with the article move but in one direction, that is toward each other. They do not otherwise change their position relative to the article, but they are forced toward each other by the movement of the wrench handle gliding with its beveled surface 11, of the carriage, against the beveled surface of the slide. The jaws therefore, remain substantially stationary relative to the clamped article, while the wrench handle is the only part which moves in, so as to speak, circumferential direction relative to the article. The grip upon the article is progressively

and proportionately increased as the pressure exerted upon the handle increases.

From the foregoing it will be evident that the surface or surfaces gripped by the jaws 5 cannot be damaged, as is the case with Stilson or other wrenches used heretofore.

Referring to the automatic re-adjusting of the jaws, this feature becomes of great importance when handling pipes or pipe fittings which are untrue around their circumference, or which have various grip facilitating means, like ribs, etc.

When, for instance, a pipe or nipple becomes flattened to an oval or elliptical shape, 15 which is very often the case by either faulty manufacture or by the use of undue force upon these articles, the wrenches used heretofore necessitate frequent re-adjusting whenever alternately gripping the compressed parts or expanded parts of the pipe, 20 whereas my device automatically adjusts itself due to the self-adjusting feature of the jaws.

While I have shown specific designs of my 25 device, be it understood that various changes and improvements may be made, as long as the main feature of my device, the automatic fine adjustment of the distance between the jaws, is adhered to.

30 I therefore reserve for myself the right to

make such changes and improvements to meet the various conditions arriving from the manifold uses to which my device is applicable, and I claim:

In a wrench, a shank, a carriage having a 35 beveled upper surface and a beveled extension adjacent to the inner surface of the shank, a beveled slide embracing the outer and the side faces of the shank and substantially open at the inner face of said shank, 40 said slide adapted to glide with its beveled surface upon the beveled surface of said carriage, a guide slot provided in the beveled extension of said carriage, a guide pin passing through the sides of said slide and 45 through said slot, a jaw arranged between the sides of said slide at a distance from the inner surface of said shank, spring means for normally keeping the jaw, attached to said slide, leaving a free space between the 50 jaw and the inner shank surface, permitting, however, its automatic motion toward the shank when an article is gripped by the jaws, whereby the distance between the latter is decreased without altering the angular relation of the jaws.

Signed at New York, in the county of New York and State of New York, this 30th day of April, A. D. 1921.

KALLE W. WIRTANEN.
